[57] CLAIM

The ornamental design for an exterior visor for vehicles, as shown and described.

DESCRIPTION

FIG. 1 is a perspective view of an exterior visor for vehicles showing my new design, the broken line representation of a fragmentary portion of a vehicle being for illustrative purposes only;

FIG. 2 is a top plan view thereof;

FIG. 3 is a front elevational view thereof;

FIG. 4 is a rear elevational view thereof;

FIG. 5 is an end elevational view thereof, the opposite end being a mirror image of that shown;

FIG. 6 is a bottom plan view thereof; and

FIG. 7 is a sectional view thereof taken along line 7—7 in FIG. 2.

FIG. 1

FIG. 2

FIG. 3

FIG. 4
